UNITED STATES PATENT OFFICE.

ALBERT E. STIRCKLER, OF NORTHAMPTON, ENGLAND.

APPARATUS FOR DRIVING TACKS.

SPECIFICATION forming part of Letters Patent No. 606,596, dated June 28, 1898.

Application filed September 26, 1896. Serial No. 607,114. (No model.)

To all whom it may concern:

Be it known that I, ALBERT EDWARD STIRCKLER, engineer, a citizen of the United States of America, residing at 200 Kettering road, 5 Northampton, in the county of Northampton, England, have invented certain Improvements in and Connected with Apparatus for Driving Tacks, of which the following is a specification.

10 My invention relates to apparatus for driving tacks, intended more particularly for use in the manufacture of boots and shoes; and it consists of means hereinafter described whereby tacks from the smallest size—say 15 three-sixteenths of an inch—upward can be conducted from a chamber or reservoir into the tacker and arranged in proper position to be separately acted on by the hammer or driver proper, so that the said tacks will be 20 caused to enter the work in a perfectly straight direction or at right angles to the surface of the work, and the tacks may be driven into the work up to their heads, or they may be driven partly into the work, so that their 25 heads will project above the surface of the work.

I will describe my invention with reference to the accompanying drawings, Figure 1 of which represents in side elevation a 30 combined tack-driving and tack-feeding apparatus constructed according to my invention. Fig. 2 is a longitudinal section of the tack-feeding portion of the apparatus drawn to a larger scale. Fig. 3 is a transverse section on the line 1 2, Fig. 2, and looking toward the closed end of the rotary tack-chamber. Fig. 4 is a side elevation, and Fig. 5 a plan, of the lower end of the chute carried by the tack-feeder. Figs. 6 and 7 are longitudinal sections at right angles to each other of the tack-driving portion of the apparatus or tacker. Fig. 6^A shows a modification of a part shown in Fig. 6 and hereinafter referred to. Fig. 8 is a transverse section on the line 3 4, Figs. 6 and 7. Fig. 9 is a vertical section of a modified form of nozzle, and Fig. 10 represents the spring-jaws detached.

The hammer or driver proper, A, of the tacker is carried by a plunger B, fitted to 50 slide up and down in the body C, constituting the handle of the tacker, the said plunger being acted on by a spring D, tending to

55 maintain it in its elevated position, it being caused to descend against the pressure of the spring by hand or other suitable means. The plunger is prevented from turning axially in the body or handle C by a projection or stud a in the body or handle entering a longitudinal slot b in the plunger B or by a projection on the plunger entering a slot in the interior 60 of the body or handle. Interposed between the lower end of the body or handle C and the nozzle E of the tacker is a box or chamber F, in which works a tack-separating blade G and in which is a groove or passage c, in 65 which the hammer or driver proper, A, works. The passage in the box F is preferably formed by bushes c', as shown in Fig. 6^A, or the said box is provided with removable plates a', as shown in Figs. 6, 7, and 8, so that when the 70 bushes or the removable plates become worn they can be readily removed and replaced by fresh pieces, thereby increasing the durability of the tacker.

The box or chamber F is divided vertically 75 through the passage c, in which the hammer or plunger works, into two parts, the said two parts being connected together by screws d and to the body or handle of the tacker by a screw-thread e on the upper end of the said box, 80 screwing into an internal thread in the lower end of the body or handle C. On the lower end of this divided box or chamber there is also provided a screwed projection f, onto which the nozzle E is screwed. 85

Connected to the box or chamber F is a chute H, formed by two plates or cheeks h, connected together by screws i, distance-pieces being interposed between the cheeks, so as to form a narrow groove, down which 90 the tacks pass into position to be acted on by the hammer or driver proper, A, the heads of the tacks being engaged in grooves or channels h² in the sides or cheeks h of the chute and the pointed ends of the tacks being down- 95 ward as they pass down the chute. At the lower ends the grooves or channels h² are curved, as shown at h³, toward and communicate with the passage c in the box or chamber F, in which the driver proper, A, works 100 and into which passage c the lowermost tack passes from the chute when the lower end of the hammer or driver proper is in a position above the lower ends of curved portion h³ of

the grooves or channels h^2 . The lowermost tack is separated from the rest of the tacks in the chute by the blade G, which is arranged to reciprocate in a slot or passage i^2 , formed through one side of the box or chamber F, the said blade being carried by an arm or lever I, centered at k to the body C of the tacker and pressed inward by a spring l, the outward movements of the said separating-blade being effected by the plunger B coming into contact with a projection m on the lever I, carrying the said separating-blade. The separating-blade fills from top to bottom the passage n, through which the tacks pass from the chute II into the passage c, in which the driver works, so that it will not be possible for the points of the tacks to enter between the blade G and the passage i^2 , in which it works, so as to cause the tacks to be directed out of their proper course, while the upper end of the said blade is in line with or so near to the lower edge of the channel h^2 in the chute, through which the heads of the tacks descend, that it is not possible for tacks even of the smallest size to enter the passage c otherwise than with their pointed ends downward.

To permit of the heads of the tacks entering the passage c when the lower end of the driver proper is below the separator-blade, the side of the driver which is toward the separator-blade is flattened or hollowed from near its lower end to a suitable distance upward, as shown at p, a shoulder p^2 being thus formed at the lower end of this flattened or hollow part, which as the driver rises catches against the lower side of the head of the tack, so as to cause the point thereof to enter the said passage c. The projection m on the lever I, which carries the separating-blade, may be adjustably fitted to the lever I, or the portion B ^{2} of the plunger, which acts on the said projection, may be adjustable in position longitudinally, as shown, so as to vary, as required, the time at which the separator-blade shall come into action, according to the length of the tacks to be driven.

In the point or end of the nozzle E of the tacker is a transverse groove or passage c^2 , in which is fitted a pair of spring-jaws C ^{2} , Fig. 10, between which jaws the shank of each tack admitted to the passage c is forced by the driver in its descent. In the contiguous faces of the spring-jaws a small hole or passage d^2 is formed, by which the tack when being driven is guided into the work in a perfectly straight direction or at right angles to the surface of the work. To insure the point of the tack entering this small hole or passage d^2 , the spring-jaws have formed in them above the said hole or passage a conical recess r, the large part of which corresponds in diameter to the diameter of the passage c, in which the driver A works, and forms a continuation of said hole or passage, and the smaller part or apex of the conical recess terminates in the small hole or passage

d^2 . The length of this conical recess from the largest part or base to the apex should not exceed, say, an eighth of an inch, so as to admit of tacks of the smallest size—say three-sixteenths of an inch long—being acted on by the driver proper before the jaws commence to open. The point of the tack enters this conical recess, and when the end of the driver A descends onto the head of the tack the point of the tack is directed by the said conical recess into the small hole or passage d^2 and is guided thereby in a straight direction while being driven into the work. The point of the tack enters the work before the head of the tack is pressed by the driver against the sides of the conical recess, after which by the further descent of the driver the head of the tack by pressing against the conical recess forces the spring-jaws apart, so as to admit of the head of the tack passing between the jaws. The end of the driver which acts on the heads of the tacks is tapered on the sides at right angles to the shoulder p^2 , as shown at c^3 , so as to readily free itself from between the jaws after driving the tack.

When the tacker is intended for "welting," or work in which the tacks are not required to be driven into the work up to their heads, the end of the nozzle E, in which the spring-jaws work, is made to extend beyond the point which the end of the driver reaches when in its lowest position to a distance equal to the length of the portion of the tack to be left projecting above the surface of the work, as shown, for instance, in Fig. 9.

To prevent the screws d' , by which the spring-jaws are connected to the body of the tacker, from becoming loose by the vibrations of the parts when the tacker is in use, the heads of the screws are each provided with a notch to receive a key e' , driven through a hole in a lug formed on the part of the spring-jaw through which the screw d' passes into the body of the tacker.

The chute II, carried by the tacker, is charged with tacks from a chamber K, preferably of a conical shape, as shown in Fig. 2, arranged to rotate on a horizontal axis. One end K $'$ of this chamber is closed, while the opposite end K ^{2} (the smallest end in the case of a conical chamber) is open and provided with an inwardly-projecting flange or rim k^2 , rotating in contact with a stationary hopper L, into which the tacks are fed and from which they pass into the rotary chamber K. The interior circumference of this rotary chamber has longitudinal flutes or grooves or is provided, as shown, with one or more longitudinal shelves or lifters l^2 , which may be adjusted in position longitudinally according to the quantity of tacks in the chamber. These shelves or lifters as the chamber rotates elevate the tacks and cause them to fall onto a concave double inclined surface II ^{2} , carried on the upper end of an inclined chute II ^{2} , fitted to reciprocate longitudinally within the chamber K. The chutes II and II ^{2} are each

provided with a narrow slot o , into which enter the shanks of the tacks falling onto the double inclined surface H^3 and down which chute the tacks slide until the said chute is filled with tacks, the heads of the tacks resting on the upper edges of the sides or cheeks of the narrow slot. The portion of the slot o in the chute which is situated inside the rotary chamber K and in the hopper L is open to receive the tacks, while the portion which is outside the said hopper is covered or partly covered by a plate or plates o^2 to prevent the tacks from being shook out of the slot in their passage down the chute by the vibrations of the apparatus.

A vibratory reciprocating movement is given to the chute H^2 by means of tappets, teeth, or projections M on the shaft K^3 , which carries the chamber K , or the said projections or tappets may be formed on or attached to the inner surface of the closed end of the said chamber. These projections or tappets as the chamber rotates act on the inner end of the chute H^2 to force the chute outward, the inward movement thereof being obtained by a spring N , attached at one end to the chute and at its other end to a fixed part of the apparatus, the spring N tending to maintain the inner end of the chute in contact with the said tappets, teeth, or projections, which may, if desired, be of different heights, so as to vary the reciprocation of the chute. To prevent any tacks from obstructing the passage of the other tacks down the chute, I provide, preferably on the hopper L , a deflector or angular piece O , somewhat like a plowshare, the said deflector being directly over the slot o in the chute H^2 to prevent the tacks from crowding on the chute and causing an obstruction. A passage is formed in this deflector, through which a projection q on a plate q^2 , fixed to and reciprocating with the chute, passes and pushes away any tacks that may tend to obstruct the passage through the chute. Instead of the plow-shaped deflector a plate screwed onto the hopper L and provided with a passage for the projection q to reciprocate in may be employed. The lower end of the chute H^2 is provided with a removable stop or gate P to prevent the tacks from passing out at the lower end of the said chute, which stop P , by the act of attaching the tacker to the chute H^2 , is moved out of the passage in the said chute by a projection on the chute H or the under side of the said chute itself depressing a spring-arm t , which carries the stop or gate P . The chute H^2 is provided with hooked projections s , with which pins or projections s^2 on the chute H engage to connect the tacker to the tack-feeder, the chutes H and H^2 , when thus connected, constituting one continuous chute, down which the tacks can pass into the passage in which the driver proper, A , works. On detaching the tacker from the chute H^2 the stop or gate P automatically closes the passage through the chute H^2 . The chamber K may be caused

to rotate only when the tacker is attached to the chute H^2 and may be set in motion by the act of attaching the tacker to the chute. A convenient way to effect this is illustrated in Figs. 1 and 2, and consists in mounting loosely on the shaft K^3 , which carries the chamber K , a pulley S , round which the driving-band from the motor passes, and to provide on the said shaft a friction or other clutching device T T^2 , the part T being formed on or attached to the pulley S and the part T^2 being fixed on the shaft K^3 . The pulley S , together with the part T of the clutch, is fitted to slide on a feather on the shaft K^3 and can be operated by a forked lever U , engaging in a groove u in the boss of the pulley S . The outer end of this lever is weighted and rests upon or against a roller u^2 , carried on one end of another lever V , centered beneath the base of the apparatus, the other end v of the said lever having an inclined surface, on which bears a roller w , carried by a bent lever W , centered to the side or lower end of the chute H^2 . When connecting the chute H of the tacker to the chute H^2 , a stud x on the chute H strikes the lever W , causing the roller w to depress the end v of the lever V and raise the opposite end thereof, the roller w^2 being thereby moved from the position shown in Fig. 2 onto a raised part u^3 on the lower end of the forked lever U , thereby forcing the part T of the clutch into frictional engagement with the part T^2 and so imparting rotation to the chamber K . On detaching the tacker from the chute H^2 the clutching device and levers by which it is operated will automatically return to the position shown in Fig. 2 and the pulley S on the shaft will continue to rotate without imparting motion to the chamber K .

Instead of starting the tack-feeding portion of the apparatus by the act of attaching the tacker thereto, as hereinbefore described, the chamber K may be constantly rotated, in which case the pulley S is fixed to the shaft K^3 and the clutch T T^2 and levers are dispensed with. In this case I provide on the lower end of the chute H^2 a lever R , having one end notched, as shown at R^2 , Figs. 4 and 5, to engage with a stationary part of the apparatus when the tacker is detached, and so retain the end of the chute H^2 , which is acted on by the tappets, out of the range of the said tappets and prevent the vibratory motion being given to the chute. By the act of attaching the tacker to the chute H^2 one of the pins or projections s^2 , which engage the hooked projections s on the chute H , presses the end R^3 of the lever R , so as to raise the end R^2 free of the stationary part of the apparatus and admit of the tappets acting on the chute H^2 to impart to it the vibratory motions, as hereinbefore described.

Although I have described a means for setting the tack-feeding device in motion by the act of attaching the tacker thereto, I do not restrict myself to the arrangement described,

except in the specific claim for the combination, neither do I restrict myself to the employment of means for starting the tack-feeding device by the act of attaching the tacker thereto nor to the arrangement described for opening and closing the passage through the chute II² by the act of attaching and detaching the tacker.

I claim—

- 10 1. In apparatus for feeding tacks, the combination of a rotary chamber to contain the tacks to be fed into the driver or tacker and means for rotating the said chamber; one or more longitudinally-adjustable ribs or lifters 15 projecting from the interior of the rotary chamber, by which ribs or lifters the tacks are elevated when the chamber rotates, a piece in the interior of the chamber having a double inclined surface or surfaces inclin- 20 ing toward each other, onto which the tacks fall from the ribs or lifters; a chute to which the double inclined piece is attached, the said chute having in the top a narrow slot or opening into which the shanks of the tacks 25 enter and down which they pass, the said tacks being supported by their heads on the top edges of the sides of the slot or opening; and means for imparting to the chute a jogging or reciprocating motion as the chamber 30 rotates so as to cause the tacks to pass down the chute, substantially as hereinbefore described.

2. In a tack-feeding apparatus, the combination of a fixed frame and a rotary chamber to contain the tacks to be fed into the tack-driver, with a chute which is mounted in longitudinal guides in the frame and into which the tacks are caused to enter by the rotation of the chamber; and a series of tapers in the interior of the chamber engaging with the chute in combination with a spring, for imparting a longitudinal reciprocating motion to the chute in its guides, substantially as described.

3. In a tack-feeding apparatus, the combination of a rotary chamber to contain the tacks to be fed into the tack-driver, the said chamber having one end open and being adapted to rotate on a horizontal, or approximately horizontal axis, with a stationary hopper against which the open end of the chamber rotates, and an inclined reciprocating chute passing through an opening in the said hopper to the interior of the chamber, means for feeding the tacks into the chute by the rotation of the chamber, and means for imparting a longitudinal reciprocating motion to the chute, substantially as described.

4. In a tacking apparatus, the combination with a chamber to contain the tacks to be fed into the tack-driver, the said chamber having one end open and arranged to rotate on a horizontal or approximately horizontal axis, a stationary hopper against which the open end of the said chamber rotates and by which the tacks are supplied to the chamber, an inclined reciprocating chute passing through an open-

ing in the hopper to the interior of the chamber, means for feeding tacks into the chute by the rotation of the chamber, and a projection on the chute reciprocating through a passage in a plate or deflector formed on or attached to the interior of the hopper, the said projection serving to prevent the tacks from obstructing the passage through the chute, substantially as hereinbefore described.

5. In apparatus for feeding tacks into a tack-driver or tacker, the combination with a longitudinally-reciprocating chute down which the tacks pass into the tacker, of a plow-shaped deflector having a passage there-through, and a projection reciprocating in the said passage in the deflector, for preventing the tacks from obstructing the passage through the chute, substantially as hereinbefore described.

6. In a tack-feeding and tack-driving apparatus, the combination of a rotary chamber to contain the tacks to be fed into the driver or tacker, an inclined reciprocating chute composed of two parts lineally connected together at their abutting ends to form a continuous chute for the passage of tacks from the rotary chamber to the tack-driver or tacker, a gate or stop at the lower end of the upper portion of the said chute to prevent the passage of the tacks therethrough when the two parts of the chute are separated, the said gate or stop being displaced or removed when connecting together the two portions of the chute and replaced when the said portions of the chute are detached, and a lever pivoted to the chute engaging with a projection to prevent the chute from reciprocating when the two portions of the chute are separated, the said lever being disengaged from the projection by the act of connecting the two parts of the chute so as to permit of the reciprocating movement of the chute, substantially as hereinbefore described.

7. In a tack-driving apparatus or tacker the combination of an inclined chute down which the tacks pass into position to be acted on by the driver proper, a separating-blade for separating the lowermost tack from the rest of the tacks in the chute, the said separating-blade being operated by the plunger which carries the driver proper, and means for varying the time in the movement of the plunger at which the separating-blade shall be operated, substantially as hereinbefore described.

8. In a tack-driving apparatus or tacker, the combination of a supply chamber or chute from which tacks pass into position to be operated on by the driver proper, a separating-blade operated so as to admit one tack at a time into the passage in which the driver proper works, a recessed or flattened part on the driver proper to admit of the head of the lowermost tack in the chute to project into the passage in which the driver proper works when the lower end of the said driver is below the separating-blade, a shoulder on the lower end of the driver proper below the said

flattened or recessed portion, which shoulder when the plunger rises comes into contact with the under side of the said lowermost tack and causes the shank of the tack to enter 5 point downward the passage in which the driver proper works, substantially as hereinbefore specified.

9. In a tack-driving apparatus, the combination of a supply-chute from which tacks 10 pass into position to be operated on by the driver proper, and spring-jaws having a conical recess and a passage for guiding the tacks in a straight direction into the work, with a driver proper, provided with a shoulder on the 15 lower end which, as the driver rises, comes into contact with the lower side of the head of

the tack and causes the shank to enter point downward the passage in which the driver proper works, the operating end of the said driver proper being tapered at the sides at 20 right angles to the said shoulder so as to be easily freed from between the said spring-jaws after driving a tack, substantially as hereinbefore described.

In testimony whereof I have signed my 25 name to this specification in the presence of two subscribing witnesses.

ALBERT E. STIRCKLER.
